UNITED STATES PATENT OFFICE.

WILLIAM R. TUTTLE, OF ROCHESTER, NEW YORK.

DISPENSING-MACHINE.

1,393,588.

Specification of Letters Patent.

Patented Oct. 11, 1921.

Application filed February 27, 1917. Serial No. 151,196.

To all whom it may concern:

Be it known that I, WILLIAM R. TUTTLE, a citizen of the United States, residing at Rochester, in the county of Monroe and State of New York, have invented a certain new and useful Dispensing-Machine, of which the following is a specification.

This invention relates to dispensing machines and has for its object a machine particularly adapted to dispense packages as lunch boxes containing food, as sandwiches, etc., and to preserve or keep the same in prime condition while in the machine, which machine is particularly simple in construction and highly efficient and durable in use; and the invention consists in the combinations and constructions hereinafter set forth and claimed.

In describing this invention, reference is had to the accompanying drawings in which like characters designate corresponding parts in all the views.

Figure 1 is an elevation of a machine embodying my invention.

Fig. 2 is a plan thereof, partly broken away.

Figs. 3 and 4 are elevations, partly broken away, taken at a right angle to each other, of the delivery mechanism, the contiguous portion of the container being shown in section.

Fig. 5 is a fragmentary detail view of the holder for the articles to be dispensed and the pusher movable along the holder.

This dispensing machine comprises generally a container, a compartment for the articles to be dispensed, a receptacle for containing a preserving or conditioning medium, also located in the container adjacent the compartment, and means for delivering the articles from the compartment.

In the illustrated embodiment of my invention, the container is provided with a receptacle for containing a preserving or conditioning medium, which receptacle is located centrally of the container, and with a plurality of compartments for the articles to be dispensed, located around the receptacle or radially relatively thereto, the receptacle being common to all the compartments and each compartment having a delivery mechanism associated therewith.

1 designates the container which is here shown as rectangular in general form, the

corners of the container constituting compartments 2 for the articles or packages to be dispensed.

3 designates the central receptacle for containing the preserving or conditioning medium as a refrigerant, when it is desired to keep the articles cold, and a warming medium when the articles are to be kept warm.

The container 1 is provided with suitable doors 4 on the four sides thereof through which the articles in the compartments are accessible, and also with the door 5 in its top through which the receptacle 3 is accessible.

The container is also provided with suitable exit slots 6 on the four sides thereof through which the articles are dispensed, and with sight and coin openings 7 and 8 in the top thereof, there being openings 7 and 8 for each compartment 2.

The delivery mechanism for each compartment may be of any suitable form, size and construction. This mechanism as here shown comprises generally a holder or magazine, a delivery member at one end of the holder or magazine, means for feeding the articles along the holder or magazine to the delivery member, and operating mechanism connected to the delivery member and said means, and operating to actuate said delivery member and said means a predetermined distance sufficient to discharge a single article at the exit slot 6 upon each operation of said mechanism.

Suitable coin controlled mechanism controls the operation of the operating mechanism.

The holder in each compartment as here shown comprises a vertical skeleton guide or chute 11 along which the articles as sandwiches or lunch packages are fed upwardly.

12 is the delivery member at the upper end of the guide 11, said member being a rotatable wheel mounted on the shaft 13 and having peripheral projections 14 movable across the upper end of the guide 11 and being of sufficient extent to pick up or wipe off the topmost article in the guide 11 and carry it around the wheel and discharge the same through the delivery slot 6 upon a suitable rest 15, these projections moving in the circular casing 16 encircling the wheel. The projections are suitably

spaced to form pockets into which the top-most article in the guide is fed, and the delivery wheel always stops in position to receive one of said articles. The casing 16 is provided with an opening opposite the sight opening 7 so that printed matter on the packages denoting the character of the articles is visible through the sight opening.

17 is the feeding member or pusher movable in the skeleton holder or magazine 11 to force the articles to the delivery wheel 12, said pusher 17 having four rollers 18 thereon movable in guides or grooves 19 provided on the frame of the holder 11, and the holder is shiftably secured to a vertically movable carrier as a belt or sprocket chain 20 movable over sprocket wheels 21, 22, the former being located near the top 20 of the container and the latter near the bottom of the container. The pusher 17 is secured to the chain 20 by any suitable coupling means, here shown as a latch 23 pivoted at 24 thereto and having a hook 25 movable into one of the chain links. The member 23 is held in its operative position by a spring 26 and is moved out of its operative position by means of a lever or wing 27 pivoted to the pusher 17 on a vertical 30 pivot and connected to a bent rod 28 which coacts with the latch. Movement of the lever 27 laterally or horizontally causes the rod 28 to move forwardly and tilt the latch 23 on its pivot to carry the hook 25 thereof 35 out of engagement with the chain 20. The wing or lever 27 is suitably connected to the rod 28 to effect the desired movement thereof, and the rod 28 is bent and engages a shoulder 29 on a forwardly extending arm 40 of the latch member 23. Said wing 27 moves about the axis 27^a of the rod 28 as a unit therewith, the pivot 27^a being vertical and carried by a fixed bearing. The rod 28 is angular, its lower arm being vertical and its upper arm substantially horizontal and pivoted at 27^a. The rod is therefore a crank arm, the vertical part of which coacts with the latch 23 some distance above the pivot 24 of said latch. As the wing 27 45 is moved horizontally on its pivot 27^a, the crank arm 28 moves therewith and the eccentric or vertical portion moves in a horizontal arc and in so doing moves forwardly and transmits a forward movement to the upper portion of the latch 23 which movement causes the latch to swing forwardly or to the left, Fig. 3 on its pivot 24 and withdraw the hook 25 of the latch out of engagement with the sprocket chain 20.

60 When it is desired to place sandwiches in the holder or magazine, the pusher or feeding member can be detached from the chain 20 and shifted toward the bottom of the container by operating the lever 27 and can 65 be again attached to the chain in any de-

sired position by releasing the lever so that the spring 26 can move the latch 23 into operative position.

In case some sandwiches remain in the holder or magazine 11 when the same is 70 being re-stocked, these sandwiches may be held from displacement downwardly when the pusher 17 is shifted, by means of a support or slide 30 which is insertible through slots 31 in the holder 11, in order to form 75 a bottom or support for said sandwiches after the feeding member or pusher 17 has been displaced. The new sandwiches are placed on the feeding member or pusher 17 below the slide 30. This slide is formed 80 with a suitable handle 32 and an upwardly extending arm 33 which braces against the outer face of the holder 11 and thus holds the support in horizontal position.

34 designates an operating member, which 85 in this form of my machine is a handle, as the machine is manually operated. Said handle is mounted upon a suitable shaft 35 journaled in the wall of the container, the shaft having a gear 36 thereon meshing 90 with a gear 37 mounted on a shaft 38 on which is also mounted a gear 39 meshing with a gear 39^a on the same shaft that the sprocket chain 21 is mounted, in order to rotate said shaft and sprocket chain to effect the feeding movement of the feeding member or pusher 17. The shaft 35 is connected to the shaft 13, on which the delivery wheel 12 is mounted, by mechanism, as the well known Geneva movement, 100 which gives an intermittent movement to the wheel 12.

Briefly this movement comprises a wheel 40 mounted on the axis of the delivery wheel 13, and having diametrically extending grooves 41 therein and also diametrically disposed pins or rollers 42, an actuating member 43 mounted on the shaft 35 on which the handle 34 is mounted and having a tooth as a roller 44 movable into the end 110 of one of the grooves 41 upon each rotation of the member 34, and a lock for normally holding the wheel 40 from rotation. Obviously, as the disk 43 is actuated one revolution, it will impart a quarter revolution to the disk 40 and the delivery wheel 12.

The lock for holding the delivery wheel 12 from movement when not being actuated, by the actuating member 43, consists 120 of a sector 45 on the member 43, the sector having a concentric groove 46 which receives one of the rollers 42.

Overthrow and stopping of the delivery wheel is controlled by a suitable ratchet and 125 pawl, and escapement mechanism unnecessary to be described herein.

The preserving medium is placed in the receptacle 3 through the top thereof, and the packages placed into the holders 11 130

through the doors. In operation, when the coin is placed in one of the slots 8, the corresponding operating mechanism is released so that the handle 34 can be operated, each 5 operation causing the delivery wheel to make a quarter turn and deliver the package to the rest or shelf 15, where it is accessible to the operator, this movement also operating the chain 20 to cause the feeding member 17 to 10 lift a single step.

When the machine comes to a stop there is a sandwich or package on the top of the delivery wheel with the printed matter thereon at the sight opening 7.

15 When it is necessary to replenish the machine, the doors 4 can be opened, the pusher 17 dropped to the bottom by operating the lever 27 and again coupled to the chain at a lower point thereon by releasing the lever 20 27, the shelf or slide 30 having been first placed between the feeding member or pusher 17 and the contents remaining in 9 the guide 11.

New articles are then placed on the pusher 25 17 beneath the old articles remaining in the guide and the slide 30 removed.

This machine is particularly advantageous in that it is particularly compact in construction and of comparatively large capacity, and further in that the articles of 30 all the compartments are kept in prime condition by a centrally located refrigerating or warming chamber.

What I claim is:

35 1. In a dispensing machine, the combination of a container having a discharge opening in the upright sides thereof, a plurality of holders in the container for the packages to be dispensed, a receptacle for a pre- 40 serving medium, the holders being arranged in upright position around the receptacle, means associated with each holder for feeding the articles upwardly toward the upper end of the holder, and a delivery member at 45 the upper end of each holder and beneath the top of the container, the container being formed with a sight opening in the top thereof through which the contents about to be delivered by said members, are visible, 50 substantially as and for the purpose described.

2. In a dispensing machine, the combination of a container having a discharge opening in one side thereof, a stationary holder for the packages to be dispensed, the holder being arranged in upright position in the container, mechanism at the top of the holder for delivering the articles including a member movable adjacent the top of the container, the top of the container having 55 a sight opening over the delivery member, said delivery member being movable under and across said sight opening, and means for feeding the articles upwardly in the holder to the delivery member, substantially 60 as and for the purpose specified.

3. In a dispensing machine, the combination of a container having a discharge opening in one side thereof, a stationary holder for the packages to be dispensed, the holder 70 being arranged in upright position in the container, mechanism at the top of the holder for delivering the articles including an overshot rotary member movable adjacent the top of the container, the top of the 75 container having a sight opening over the delivery member, said delivery member being movable under and across said sight opening to carry the articles to be discharged opposite the sight opening, means 80 for feeding the articles upwardly in the holder to the lower side of the delivery member, and means connected to the operating member for actuating the feeding means a predetermined amount during each operation of the operating member, substantially 85 as and for the purpose set forth.

4. A dispensing machine comprising a container, mechanism in the container for feeding the articles to be dispensed comprising a carriage including a belt, a pusher for feeding the articles carried by the belt, means for detachably coupling the pusher to the belt and operable to permit the pusher to be shifted along the belt, substantially as 90 95 and for the purpose specified.

In testimony whereof, I have hereunto signed my name, at Rochester, in the county of Monroe and State of New York, this 4th day of January, 1917.

WILLIAM R. TUTTLE.
